(57) **CLAIM**

The ornamental design for a solar panel arrangement, as shown and described.

DESCRIPTION

FIG. 1 is a top perspective view of a solar panel arrangement, showing my new design.

FIG. 2 is a front view thereof.

FIG. 3 is a side elevational view thereof.

FIG. 4 is a rear elevational view thereof.

FIG. 5 is a top plan view thereof.

FIG. 6 is a bottom plan view thereof; and,

FIG. 7 is a bottom perspective view thereof.

The broken lines shown represent unclaimed subject matter and form no part of the claimed design.
